UNITED STATES PATENT OFFICE.

PATRICK MCLOON, OF GLENCOE, MISSOURI, ASSIGNOR OF ONE-HALF TO PHILIP J. DAUERNHEIM, OF ST. LOUIS, MISSOURI.

STEAM-BOILER.

1,135,908.

Specification of Letters Patent. Patented Apr. 13, 1915.

Application filed January 22, 1912. Serial No. 672,738.

To all whom it may concern:

Be it known that I, PATRICK MCLOON, a citizen of the United States, and resident of Glencoe, St. Louis county, Missouri, have 5 invented certain new and useful Improvements in Steam-Boilers, of which the following is a specification containing a full, clear, and exact description, reference being had to the accompanying drawings, forming 10 a part hereof.

My invention relates to an improved steam boiler and consists in the novel construction hereinafter described and pointed out in the annexed claim.

15 The object of my invention is to provide a steam boiler the furnace of which shall effectually operate to consume the smoke, and which steam boiler shall be simple in construction and economical in operation.

20 In the drawings Figure 1 is a sectional end elevation of my improved steam boiler and its setting; Fig. 2 is a sectional side elevation of same; Fig. 3 is a sectional plan view in detail showing the construction of the 25 fire openings formed in the water legs of the boiler; and Fig. 4 is a sectional side elevation of the boiler and its setting, together with the steam drums.

The boiler preferably has a cross section 30 in the form of an inverted U having the opposite water legs 1, the upper edges of which are connected by a water arch 2, the inner and outer walls of both water legs and water arch being connected and 35 strengthened by the usual stay bolts 3.

The construction just described produces a boiler having a large fire box 4 the opposite ends of which are closed by the furnace walls.

40 The front wall 5 is built within the front of the said fire box, and the rear wall 6 is built within the rear of the fire box thereby closing the front and rear of the fire box except that the said front wall is provided 45 with one or more fire doors 7, one or more ash pit doors 8, and the rear wall is also provided with one or more fire doors 7 and one or more ash pit doors 8, so that the fire box may be fired from either front or rear 50 or both front and rear.

9 indicates furnace grate bars, which may be of any preferred construction and supported at their outer ends by the fire box end walls, and at their inner ends by suitable 55 I-beams 10 or other common devices which

extend laterally across the interior of the fire box.

The water arch 2 is provided at its opposite ends with the usual man holes 11 for the purpose of enabling the arch to be 60 cleaned and repaired.

12 indicates a series of fire openings formed in the opposite water legs 2 in a plane above the grate bars 9 and in a plane a distance below the water arch 2, for permitting the egress of the smoke and flame 65 from the fire box.

The boiler above described may be provided with any common form of boiler setting and in the present instance I have 70 shown the boiler set in brick work or other masonry arched above the water arch 2 as shown at 13 and which provides a comparatively wide space which is of inverted U-shape in cross section and extends completely around the exterior of the boiler at a uniform distance therefrom, and thereby providing a combustion chamber 14 exterior of the boiler into which passes smoke and flame from the fire openings 12. 75

15 indicates the smoke stack which is placed at the top of the arched wall 13 with its interior in communication with the combustion chamber 14.

16 and 17 indicate a pair of steam drums 85 which are located as shown in Fig. 4, in the same horizontal plane, but also in a plane a considerable distance above the boiler and each of said drums is connected to the boiler by means of circulatory pipes 90 18 and 19, all of which pipes are connected to the bottom of said drums.

The lower ends of the circulatory pipes 18 are connected to the water-arch 2, so that the water and steam will pass upwardly through said pipes into said drums, while the pipes 19 have their lower ends connected to the lower portion of the water-legs 1, so that the water from the said 100 steam drums may pass downwardly from the pipes 19 and enter said water-legs.

The numeral 20 indicates the steam pipe which is connected to the steam space of each of the steam drums 16 and 17 for the purpose of permitting the steam to be carried to a steam engine or other apparatus designed to utilize the steam. 105

The operation is as follows: The smoke and flame from the fire-box 4 pass upwardly into the space immediately beneath the 110

water-arch 2, where they thoroughly commingle, and then they are drawn downwardly and pass out of the fire-box through the fire-openings 12 into the exterior combustion chamber 14, where the smoke is thoroughly consumed. The products of combustion make their exit from the combustion chamber 14 through the smokestack 15. A common water line, (as indicated by the dotted lines in Fig. 4) is of course maintained in each of the steam drums 16 and 17. The pipes 18 are purposely made larger than the pipes 19, so that the steam and water passing upwardly from the boiler into the steam drums may meet with as little frictional resistance as possible.

My improved boiler possesses certain advantages which are readily apparent, and I found in practice that it effectually consumes the smoke when bituminous coal is burned in the furnace.

The said steam drums 16 and 17 might also be called "separating drums" for the reason that the steam is therein separated

from the water, in accordance with the well known laws, which need not be herein explained.

What I claim is:

In combination with a furnace setting having a centrally located stack opening 30 in its top, a boiler extending throughout the length of the setting and spaced therefrom at its sides and top and comprising an arch and water legs constructed as a unit, each of the water legs having openings at 35 intervals therethrough, placing the fire zone of the boiler in communication with both sides of the space between the boiler and setting, substantially as shown and for the purposes stated.

In testimony whereof, I have signed my name to this specification, in presence of two subscribing witnesses.

PATRICK McLOON.

Witnesses:

E. L. WALLACE,
JOHN C. HIGDON.
